LANCELOT MARTIN SIMPSON, OF THORNER, NEAR LEEDS, ENGLAND, ASSIGNOR TO ASSOCIATED TELEPHONE AND TELEGRAPH COMPANY, OF CHICAGO, ILLINOIS, A CORPORATION OF DELAWARE

ELECTRICAL RELAY ARRANGEMENT

Application filed January 20, 1930, Serial No. 421,969, and in Great Britain April 16, 1929.

The present invention relates to electrical relays and is more particularly concerned with improved arrangements for permitting a plurality of relays, in addition to operating electrical contacts, to control one another mechanically.

According to one feature of the invention the energization of an exciting coil under certain conditions serves to operate a set of contact springs and under different conditions serves to prevent the operation of the contact springs.

According to another feature of the invention in a hunting switch for use in telephone or like systems the operation of the test relay controls an interlocking member by means of which the subsequent operation of the relay which initiates the hunting operation is prevented until said relay has de-energized following the de-energization of the test relay.

A further feature of the invention is that in a subscriber's rotary line switch for use in telephone systems the operation of the cut-off relay on an incoming call completes a circuit for the line relay and operates a mechanical stop to prevent the movement of the line relay armature, the engagement of this armature with the stop serving to prevent the stop returning to its normal position until the line relay has de-energized.

These features and others not specifically mentioned at this point will be better understood from the following description of one method of carrying the invention into effect which should be taken in conjunction with the accompanying drawing. This shows the invention applied to a subscriber's rotary line switch of the homing type as used in automatic telephone systems. It will be understood, however, that the invention is not limited to this particular application and that it may be employed advantageously under a number of other conditions such as will readily occur to those skilled in the art.

Referring now to the drawing, Fig. 1 shows a front view and Fig. 2 shows a side view of a subscriber's line and cut-off relays provided with the mechanical interlocking arrangement according to the invention; while

Fig. 3 shows details of the circuit arrangement of the line switch with which the relays are associated.

Referring now particularly to Figs. 1 and 2, the relays are mounted in known manner on a base plate 10 which may be suitably supported on a rack or the like. The relay cheeks are indicated by 11 and the windings by 12, and it will be noted that the upper relay which is the subscriber's line relay is provided with a copper slug 13 which surrounds the end of the relay core and renders the relay slow acting.

The interlocking is effected by a bell crank lever 14 which is shown more clearly in Fig. 1 and which is pivoted to the front plate 15 by means of the screw 16. The shorter limb 17 of the lever 14 engages with an extension 18 of the armature 19, of the lower relay, while the longer limb 20 is notched as shown for engagement with the pawl 21 which is an extension of armature 22 of the upper relay.

The pawl 21 which is more clearly shown in Fig. 2 is pivoted by means of the screw 23 so that it normally rests under the influence of gravity against the small top screw 24 which rides in a convenient slot cut in the end of the pawl.

It must be mentioned that the pivot screws 16 and 23 are provided at their heads with a boss on which the lever and pawl may turn, and this boss is of slightly greater length than the thickness of the lever or pawl, so that the pivot screws can be screwed up tightly without affecting the free movement of the lever and pawl.

When both relays are in the non-operated position both the lever 14 and the pawl 21 are held by gravity in the position shown in the drawing, i. e. with the pawl arm slightly higher than the end of the longer limb 20 of the lever 14, and if the circuit operation is such that the upper relay is now energized, the armature 22, which is pivoted by means of the tongues 25 let into suitable slots in the base plate 10, will now fully operate, thereby carrying with it the pawl 21 into a position just above the V shaped notch in the end of the lever 14. If now the lower relay is energized the movement of the associated

armature 19 will move the lever 14 owing to the engagement of the extension 18 with the shorter limb 17 of the lever. By this means the longer limb 20 will be raised a proportionate distance thereby carrying with it the pawl 21 which it will be remembered was moved into a position over the V shaped notch in the end of the lever 14 due to the operation of armature 22 of the upper relay. Hence when the upper relay is subsequently de-energized the armature 22 will return to its normal position owing to the pressure exerted by the contact springs 26, and by this means the pawl 21 will be caused to ride over the V shaped notch so that it drops by gravity over the end of the lever against the stop screw 24.

In this position the pawl is now opposite the end of the lever 14 and assuming now that the upper relay is again energized, the pawl will come into engagement with the lever and the armature 22 will only be able to move a distance depending upon the adjustment of said lever. This distance may of course be so small as to prevent the contact springs from operating at all. Furthermore, in case the lower relay should be released meanwhile, the pressure exerted by the pawl 21 against the end of the lever 14 will be sufficient to hold the lever in its operated position independent of the condition of the lower relay, so that by this means the upper relay may be rendered in-operative throughout its energization at this stage. It will be noticed from the drawing that the lower edge of the pawl arm is shown bevelled so that it may ride more easily over the V shaped notch in the lever. Conditions such as those just outlined occur in the normal operation of a subscriber's line switch as illustrated in Fig. 3 and the circuit changes involved will now be considered in detail.

In this case the upper relay of Figs. 1 and 2 is the line relay L and the lower relay the cut-off or switching relay K. When a subscriber originates a call, his line relay L is operated first over the loop including his instrument, thereby moving the pawl into position over the V-shaped notch in the lever. Line relay L at armatures l_1 and l_3 closes a circuit for the rotary magnet DM which can be traced over the interrupter springs I, armature k_4 , armature l_3 , private wiper P and the home position contact in its bank, armature l_1 to earth. The rotary magnet DM is operated and steps the switch until an unearthed contact on the private wiper P is encountered. During the stepping the switching relay K is short-circuited as follows: earth, over private wiper P, armature l_3 , armature k_4 , relay K, home position contact of wiper H to earth over private conductor P. The switching relay K operates when a free trunk is found thus causing the lever to lift the pawl in the manner already

described. Relay K at armatures k_1 and k_2 opens the original energizing circuit of relay L, at armature k_3 closes a point in the circuit of private conductor P, at armature k_4 prepares a circuit for the meter M and at armature k_5 closes a point in a circuit for relay L. Relay L releases after a suitable slow period, due to its copper slug and as the armature moves into its normal position, the pawl is caused to ride over the end of the V-shaped notch so that it drops into its normal position.

Moreover, upon the full release of relay L earth via the resting armature of l_1 will then be extended by way of the now operated armature k_5 to the winding of relay L, and accordingly relay L again becomes energized, but is prevented from operating at this stage owing to the pawl coming into engagement with the end of the lever which is held up by relay K.

When, however, the subscriber receives a call, the switching relay K is energized before the line relay L due to the extension of earth over the private conductor P, and in this case the lever is lifted before the circuit is completed to the line relay L. Hence, upon the full operation of relay K, line relay L will become energized over the circuit previously traced, but operation of the armature will be prevented owing to the action of the pawl and lever.

Suppose now that the system is arranged for calling party release and that the calling subscriber clears before the called subscriber, relay K of the called subscriber's lineswitch will be released upon the removal of earth from the private conductor P when the switch train is dropped, and although it will be observed that the circuit to relay L is opened at armature k_5 , the relay holds under the influence of the copper slug until an alternative circuit is closed by way of the subscriber's loop and the now resting contacts of armatures k_1 and k_2 . By this means it will be appreciated from the previous description of the interlocking arrangement, that relay L will be prevented from operating during this condition, and therefore the needless operation of the lineswitch and the selection of an outgoing line is prevented.

Assuming that the called subscriber clears before the calling subscriber, on the subsequent release of the calling subscriber, relays K and L will de-energize and there will be no further circuit completed for relay L.

Such a feature is of particular utility in a register controller system where not only would the lineswitch be operated, but register equipment would be needlessly occupied, thus necessitating the provision of this equipment in larger quantities than would otherwise be required. Moreover, as the lineswitches are of the type which return to a home position they make a complete revolution

tion unnecessarily and their life must be definitely shortened.

Claims:

1. In a relay arrangement, a first and a second relay, an armature for each of said relays, an interlocking lever controlled by the armature of said first relay, a pawl member controlled by the armature of said second relay, means for energizing said first relay to move its armature and operate said interlocking member, means for energizing said second relay to move its armature and operate its pawl into engagement with said interlocking member, and means for deenergizing said first relay to restore its armature only, said pawl preventing the release of said interlocking member. 70
  2. In a relay arrangement, a first and a second relay, an interlocking member controlled by said first relay, a pawl member controlled by said second relay, means responsive to the energization of said first relay for operating said interlocking member, and means responsive to the energization of said second relay for operating said pawl member into engagement with said interlocking member and for maintaining said interlocking member in its operated position after said first relay is deenergized. 75
  3. In a hunting switch for telephone or like systems having access to a plurality of trunks, a test relay for controlling the hunting operation of said switch to select one of said trunks, a line relay for initiating the hunting operation, an interlocking member controlled by said test relay, means responsive to the energization of said test relay before said line relay for operating said interlocking member to prevent said line relay from initiating the hunting operation when it energizes, and means responsive to the deenergization of said line relay after said test relay has deenergized and released said interlocking member for again energizing said line relay to initiate the hunting operation of said switch. 80
  4. In a subscriber's rotary lineswitch for use in telephone systems, a cut-off relay and a line relay each having an armature, an interlocking member controlled by said cut-off relay armature, means responsive to an incoming call to said lineswitch for energizing said cut-off relay to move its armature to operate said interlocking member and to complete an energizing circuit for said line relay, said interlocking member engaging said line relay armature to prevent its movement after said line relay energizes, and means on said line relay armature for preventing the release of said interlocking member after said cut-off relay has released its armature until said line relay has deenergized and released its armature. 85
  5. In a subscriber's rotary lineswitch for telephone systems having access to a plural-
- ity of trunks, a line relay having contact springs for initiating the trunk hunting operation of said switch, a test relay for controlling said hunting operation, means responsive to an outgoing call from said lineswitch for energizing said line relay to operate its contact springs to initiate the hunting operation of said switch, means for energizing said test relay when a free trunk is found and for deenergizing said line relay, a circuit connection completed by said test relay through the contact springs of said line relay for again energizing said line relay, and means controlled by the operation of said test relay for preventing the operation of said contact springs at the time said line relay is again energized. 90
6. In a relay arrangement, a first and a second relay, a pivoted interlocking member controlled by said first relay, a second pivoted member controlled by said second relay, means responsive to the energization of said first relay for operating said interlocking member to prevent the operation of said second pivoted member when said second relay is energized, means when said second relay is energized for holding said second pivoted member against said interlocking member and maintaining it in its operated position after said first relay is deenergized, and means if said second relay is initially energized for operating said second pivoted member to ride over the end of said interlocking member and after said interlocking member is operated by the energization of said first relay and said second relay deenergizes, restores to its normal position, said interlocking member thereafter acting as a stop to prevent further operation of said second pivoted member. 95
7. In a relay arrangement, a first and a second relay, an armature on each of said relays, an interlocking member controlled by the armature of said first relay, a pawl member controlled by the armature of said second relay, means for energizing said first relay to move its armature and operate said interlocking member to a position opposite said pawl member, means for energizing said second relay to attempt to move its armature, the movement of said second relay armature being prevented by said pawl member engaging said interlocking member, said pawl member maintaining said interlocking member in its operated position after said first relay has deenergized and released its armature, and means when said second relay is energized first and then said first relay is energized for operating said pawl and interlocking members without any effect on the respective movements on said armatures. 100
